[57] CLAIM

The ornamental design for a pooling container for parenteral fluids and the like, as shown.

DESCRIPTION

FIG. 1 is a perspective view of the right and back sides of a pooling container for parenteral fluids and the like showing our new design;

FIG. 2 is a right side elevational view thereof;

FIG. 3 is a top plan view thereof;

FIG. 4 is a back elevational view thereof; and

FIG. 5 is a front elevational view thereof.

The undisclosed bottom of the pooling container is conventional.

FIG. 1**FIG. 2****FIG. 3****FIG. 4****FIG. 5**
